EJECTOR APPARATUS

Filed July 21, 1945

UNITED STATES PATENT OFFICE

2,519,531

EJECTOR APPARATUS

George A. Worn, Greenwich, Conn., assignor to
 The Lummus Company, New York, N. Y., a corporation of Delaware

Application July 21, 1945, Serial No. 606,439

3 Claims. (Cl. 230—95)

1 This invention relates to improvements in gas ejector apparatus.

An important object of the invention is to provide improved ejector apparatus having provision for conducting combustion, for employment of hot gaseous products of the combustion as motive fluid for the ejector and also for employment of the combustion products to operate a compressor for supplying gas to support the combustion.

Other objects of the invention will appear from the following description and the accompanying drawing:

In the drawing,

Fig. 1 is a vertical longitudinal sectional view of an ejector apparatus embodying the invention; **15**

Fig. 2 is a view similar to Fig. 1 showing a modified form of the apparatus.

The ejector apparatus shown in Fig. 1 includes a tubular member 1 which forms a relatively small combustion chamber. At one end thereof, this chamber bears a jet nozzle 2 defining a restricted discharge port for the chamber. A burner 3 for fluid fuel is mounted within the chamber and is supplied with fuel through a pipe 4. The burner is directed axially of the combustion chamber and toward the discharge nozzle 2. Any suitable means may be employed for igniting the fuel at the burner, a spark plug 5 being indicated for that purpose in the present instance.

A casing 6 forming a gas chest surrounds the jet nozzle 2 and has an inlet nozzle 7 at its under side. A pipe 8 is connected to the chest nozzle 7 for flow of air or other gas to the chest. An entrainment nozzle or "diffuser" 9 is mounted in axial alignment with the jet nozzle to receive the jet discharged from the latter. In the present instance, the entrainment nozzle is of the Venturi type, being flared from a medial point outwardly to its opposite ends. Its form may be varied, however. The receiving end of the diffuser projects into the chest 6 through an aperture in the latter and has a flange 10 secured in sealed connection with the chest, around said aperture. Similarly, the jet nozzle 2 and the adjacent end portion of the combustion chamber 1 project into the chest through an opposite aperture in the chest, and the chamber 1 has a flange 11 secured in sealed connection with the chest around said aperture.

Air under pressure, together with gaseous products of combustion, is supplied to the combustion chamber 1 by means of a compressor 12a. In the present instance, the compressor is of a turbine type and it is driven by a motor 20 of a gas

2 turbine type, through coupled shafts 21. The compressor 12a has an air inlet 13 at one end thereof and an air outlet 14a at its opposite end. Said outlet is in delivery connection, through an elbow union 17, to one end of a tubular combustion chamber 18 having a fluid fuel burner 19 mounted therein and directed toward the opposite end of the chamber. Said opposite end of the chamber is in delivery connection with the inlet of the power turbine 20, and the outlet of the power turbine is in delivery connection with the combustion chamber 1 through a pipe 15 and an elbow connection 16. Thereby, an air delivery path is established from the compressor to the combustion chamber 1. The burner 19 within the combustion chamber 18 leading from the compressor is supplied with fluid fuel through a pipe 19a. A spark plug 5a is indicated for igniting the fuel at the burner.

Combustion at the burner 19 energizes the air within the chamber 18, and the hot air and products of combustion pass to the turbine 20 and operate it to drive the compressor 12a and then pass to the combustion chamber 1 of the ejector. The air so supplied supports combustion within the chamber 1 and the compressor is operated to deliver air in amount in excess of that required for combustion so that the excess air, together with the gaseous products of combustion will serve as the motive fluid of the ejector. The propulsive force of the air will be greatly increased by the combustion heat so that a powerful jet of the motive fluid will be discharged through the nozzle 2 and the diffuser 9. The jet will entrain air or other gaseous media within the chest and the pipe 8 and discharge it through the diffuser. The pipe 8 may lead from a confined zone and the ejector may be employed for evacuation of gaseous media or for other purposes.

Fig. 2 shows a modification of the means for supplying motive fluid to the ejector. A chamber 22 is substituted for the combustion chamber 1 of Fig. 1 and bears the nozzle 2. Within its outer end, the chamber 22 has a gas power turbine 23. An air compressor 12 has its outlet in delivery connection, through an elbow union 24, with one end of a tubular combustion chamber 25. A burner 26 is mounted within the chamber 25 adjacent said end and directed toward the opposite end of the chamber, and the chamber is in delivery connection at said opposite end thereof with the inlet of the turbine 23.

In the operation of the apparatus shown in Fig. 2, combustion within the chamber 25 of

fluid fuel supplied through a pipe 26a to the burner 26 energizes the air; and the hot air and products of combustion operate the turbine 23 which, in turn, drives the compressor 12 through coupled shafts 27. After passing through the turbine 23 the hot air and combustion products are discharged from the chamber 22, through the nozzle 2 and form the motive fluid jet.

In both of the disclosed forms of the invention both the supply and the energization of the motive fluid are accomplished in a simple manner solely by combustion of fuel within the apparatus itself; no extraneous equipment is needed for generating and supplying the motive fluid. Thereby, substantial economy in equipment, 15 operation and servicing is obtained.

While two satisfactory embodiments of the invention are disclosed, the apparatus is susceptible of further modification of details. It will be understood therefore, that the disclosure 20 is merely illustrative and in nowise limiting and that the invention comprehends such modifications as will fall within the scope of the appended claims.

Having thus fully described my invention, 25 what I claim as new and desire to secure by Letters Patent is:

1. Ejector apparatus comprising a diffuser, a constantly open jet nozzle disposed adjacent one end of said diffuser to discharge a jet of motive 30 fluid into the diffuser, conduit means constructed and arranged to conduct to said end of the diffuser fluid to be entrained and exclude entry of other fluid, a combustion chamber from which said jet nozzle opens directly, a burner for fluid fuel within said chamber, a conduit for supplying combustion-supporting gas to said chamber, a compressor connected to said conduit to force 35 said gas therethrough, a burner for fluid fuel disposed for combustion within said conduit at a point between said compressor and said chamber, a turbine connected to said conduit at a point between the second-mentioned burner and said chamber and adapted to be driven by gas flow through the conduit, and an operative connection between said turbine and said compressor for driving the latter to supply the combustion chamber with said gas for continuous combustion and continuous discharge of the hot gaseous contents of the chamber through said jet nozzle as 50 the motive fluid.

2. Ejector apparatus comprising a diffuser, a constantly open jet nozzle disposed adjacent one end of the diffuser to discharge a jet of motive fluid into the diffuser and entrain an- 55

other fluid, a combustion chamber from which said jet nozzle opens directly, a burner for fluid fuel within said chamber, a conduit for supplying combustion-supporting gas to said chamber, a compressor connected to said conduit to force said gas therethrough, a burner for fluid fuel disposed for combustion within said conduit at a point between said compressor and said chamber, a turbine connected to said conduit at a point between the second-mentioned burner and said chamber and adapted to be driven by gas flow through the conduit, and an operative connection between said turbine and said compressor for driving the latter to supply the combustion chamber with said gas for continuous combustion and continuous discharge of the hot gaseous contents of the chamber through said jet nozzle as the motive fluid.

3. Ejector apparatus comprising a diffuser, a constantly open ejector nozzle disposed adjacent one end of said diffuser to discharge a jet of motive fluid into the diffuser and entrain another fluid, a conduit in gas delivery connection with said nozzle, a compressor connected to said conduit to deliver combustion-supporting gas thereto and force gas through the conduit, a burner for fluid fuel disposed for combustion within said conduit at a point between said compressor and the jet nozzle, a turbine connected to said conduit at a point between said combustion point and the jet nozzle and adapted to be driven by gas flow through the conduit, and an operative connection between said turbine and said compressor for driving the latter to supply the conduit with combustion-supporting gas at said combustion point and cause a continuous delivery of hot gas through the conduit to the jet nozzle and continuous discharge of the hot gas therefrom as the motive fluid.
